UNITED STATES PATENT OFFICE.

JACOB OCHSNER, OF ZURICH, SWITZERLAND.

DEVICE FOR THE REMOVAL OF REFUSE.

1,373,756.

Specification of Letters Patent.

Patented Apr. 5, 1921.

Application filed August 25, 1917. Serial No. 188,100.

To all whom it may concern.

Be it known that I, JACOB OCHSNER, citizen of Switzerland, residing at Zurich, have invented certain new and useful Improvements in Devices for the Removal of Refuse, of which the following is a specification.

This invention relates to improvements in refuse receptacles and more particularly to a portable receptacle having an auxiliary bucket adapted to be attached to the side of the box, and when filled the bucket may be swung over the box and emptied.

The principal object of the present invention is to provide an efficiently operated device of this character wherein a portable receptacle may receive the contents of auxiliary buckets without exposing the contents of either to view or allow the escape of obnoxious odors, and means whereby a portion of the lid of the receptacle may be automatically removed to permit the bucket to deposit its contents into the receptacle.

The invention consists in the structural features and combination of parts herein-after fully described with reference to accompanying drawings wherein,

Figure 1, is a vertical sectional view of a refuse receiving receptacle showing the lid closed and an auxiliary refuse bucket suspended at the side of the receiving receptacle.

Fig. 2, is a sectional view similar to Fig. 1, except that the auxiliary bucket is shown in its raised position.

Fig. 3, is a detail view of a portion of the receptacle cover and a part of the cover of the bucket engaging the stop pin carried by the cover of the receptacle.

Referring to the drawing 1 denotes a cart box, which may be constructed in accordance with any of the well known types now in use, but in order to illustrate the invention I prefer to show a cart box consisting of two compartments mounted on opposite sides of centrally located longitudinal beams of the refuse cart. The rear walls 2, of said compartments are designed to extend in a vertical plane and adapted to be held together by any suitable means as shown in Fig. 1. The journal 4 of the arched cover 3 of the cart box revolves in the bearing eyes 5 which are fixed to the sides 6 of the cart box 1.

The cover 3, of the box 1, is provided with an arcuately formed guide channel 7, arranged above the end walls 6, and designed to accommodate a slide cover 9. The slide

cover 9, is of sufficient area to completely cover a filling opening 8, formed in a portion of the receptacle cover 3, said opening 8, is located adjacent the outer wall of the receptacle 1, to provide ready access to the interior of the latter. A suspension bar 10, is secured at its opposite ends to the end walls 6, of the receptacle 1, and has an intermediate portion extending parallel to the outer edge of said receptacle.

An auxiliary bucket 12, which may be of any suitable size or form is provided with a hook member 13, adapted to hook over the suspension bar 10. It will be noted that the bucket 12, may be readily removed or replaced, and in order that this may be accomplished as easily as possible I simply permit the hook 13, to remain open a sufficient distance to allow it to pass over the suspension bar 10. The bucket 12, is provided with a cover hinged to the bucket at a point diametrically opposite to the hook 13. A slotted lip 14, projects outwardly from the free edge of the bucket cover and is slightly upturned at its extreme end. The lip portion 14, of said lid is adapted to overlie the edge of the bucket 12, and to protrude over the outer edge of the receptacle wall. The slot in the lip 14, engages a vertical pin 11, carried by the slide cover 9. An angle stop bar 15, spaced slightly back of the pin 11, is adapted to receive the end of the lip 14, when the latter is moved rearwardly.

In the operation of the device, the slide cover is normally over the opening 8, in the cover 3, of the receptacle 1, and the bucket 12, suspended by the hooks 13, at the side of the receptacle 1. The lid of the bucket 12, is in closed position and the slot in the lip 14, engaged by the pin 11, on the movable cover 9. The buckets are usually filled and closed by their covers before hooking them on to the suspension bar 10. Assuming this to be the case, the bucket 12, as shown in Fig. 1, is hooked over the suspension bar 10, in readiness for the dumping operation.

As the bucket is swung about the bar 10, the lid of the bucket will ride forward until the pin 11, engages the rear wall of the slot in the lip 14, the end of the lip 14, also seats against the angle stop 15. This position in the operation of the device is clearly shown in Fig. 3, of the drawings. Upon further upward arcuate movement of the bucket 12, the lip 14, seated against the stop 15, on the slideable receptacle cover will compel the lat-

ter to retreat rearwardly between the guides 7, and at the same time the lid of the bucket is gradually swinging away from the mouth of the latter. As shown in Fig. 2, the receptacle slide lid 9, has moved to its extreme rearward position and the bucket is inverted over the filling opening 8, to discharge the contents into the receptacle 1, without exposing the interior of the latter in so doing. The lid of the bucket 12, lies over the closed portion of the cover 3, when the bucket cover is fully extended, and lies approximately parallel therewith.

The return of the empty bucket 12, to its initial position is accomplished by simply swinging the latter back about the bar 10, and the forward end of the slot in the lip 14, will draw the receptacle cover back over the filling opening 8. The bucket may then be either removed or refilled and the above described operation repeated.

The triangular movement of the bucket and its cover initiating the opening and closing of the receptacle cover 9, provides a very simple means whereby the latter is withdrawn from over the filling opening 8, by the arcuate movement of the bucket cover as the bucket 12, is swung about the bar 10, and then redrawing the cover 9, to its initial position when the bucket is returned to the side of the receptacle.

I claim:

1. The combination with a refuse receiv-

ing receptacle having a portion of its top open, of a sliding cover for said open portion of the receptacle, a refuse bucket pivotally suspended adjacent said opening, and means carried by the bucket and having a lost motion connection with said cover whereby when the bucket is turned about its pivot said cover is slid away from the opening and the contents of the bucket may be emptied into said receptacle through the opening in the top thereof.

2. The combination with a refuse receiving receptacle having a portion of its top open, of a cover slidably mounted on the top of the receptacle and adapted to keep said open portion closed, a projecting pin carried by said cover, a pivot mounted on said receptacle adjacent the opening therein, a bucket mounted on said pivot, and a hinged cover for said bucket having an extended slotted portion engaging the projecting pin of the sliding cover whereby when said bucket is moved about its pivot the cover thereof will slide the cover of the receptacle away from the opening therein and permit discharge of the contents of the bucket into the receptacle.

In testimony whereof I affix my signature in presence of two witnesses.

JACOB OCHSNER.

Witnesses:

FRIEDRICH HEILNER,
KUST EGENER.
